LOCKING MECHANISM FOR DOORS

James W. Shannon and Louis M. Hathaway, Ingleside, Tex., and James E. McKee, Wilmington, Del.

Application November 12, 1940, Serial No. 365,226

2 Claims. (Cl. 292—182)

This invention in its broader aspects has reference to securing mechanism for doors, furniture drawers and analogous movable units.

More particularly, the present improvements relate to devices adapted for locking aligned doors to an intervening jamb such as the side doors of automobiles, passenger cars and so forth, and wherein it is highly desirable that they be firmly held against accidental or deliberate opening by occupants while the automobile or car is in motion.

More specifically the present improvements have reference to devices of the type operative to automatically lock the rear doors of four-door automobiles or other cars when the front ones are closed, so that said rear doors cannot be accidentally or otherwise opened until the front ones are released.

Devices of the species referred to in the preceding paragraph while effective in use are mostly of complicated construction; involve a specially-shaped coactive jamb or center post; comprise numerous essential parts; and require great care in installation, with attendant expenditure of much time and labor.

The primary object of this invention is to furnish a locking device for the above specified purpose that includes but few cooperative parts; which is positive in action; is adapted for application to all standard types of four-door cars, whether new or old; and is capable of installation in a minimum of time with resultant saving of labor and expense.

Another object is to provide a door locking device of the indicated species which can be applied to the center post of all types of four-door automobiles and cars, or to individually movable adjoining drawers and similar units, without damaging, defacing or altering the shape or conventional section of the respective doors and center post.

A further object is to provide a door-locking device in which the operative parts are housed in a single casing designed for easy attachment laterally across a car center-post between the confronting edges of the aligned doors.

Other objects with ancillary advantages of this invention will become apparent from the following description, considered in conjunction with the accompanying drawing, of typical embodiments thereof; and wherein like reference characters designate corresponding parts in all the views; while the concluding claims more particularly define the features of novelty over the prior art.

In the drawing:

Fig. 1 is a horizontal section through a four-door automobile jamb or center post with the locking device of this invention assembled and secured therein; said section being taken approximately on the plane I—I in Fig. 4.

Fig. 2 is a plan-section on the line II—II of Fig. 4, with an adjunctive striker socket fitted in the rear door edge confronting the center-post, and with said door un-locked.

Fig. 3 is a corresponding section to the preceding, showing the parts in a different position or with the rear-door locked, and an added wear plate fitted in the rear side edge of the front-door.

Fig. 4 is a fragmentary face elevation of the forward side of the center-post, or as approximately seen when looking from the left towards the right-hand of Fig. 1, such elevation being drawn in a plane at right-angles to said figure.

Fig. 5 is a detail section on the plane V—V of Fig. 2.

Fig. 6 is a similar section on the plane VI—VI of Fig. 3.

25 In the following detailed description of the preferred embodiment of this invention, shown by the single sheet of illustrative drawings, specific terms will be employed for the sake of clarity, but it is to be understood that such terms 30 are used in a descriptive sense and not for purposes of limitation, each specific term being intended to include all technical equivalents which operate in a similar manner to accomplish an analogous purpose.

35 In accordance with this invention, and referring to Figs. 1 to 6 of the drawing, the improved car rear-door locking device, therein shown, preferably comprises a tubular casing 1 having an end wall 2 provided with a concentric aperture 3, and, at the other end, an angle-section surrounding flange 4 for seating reception in the corresponding diameter recess 5 of a rectangular plate 6, and rigid attachment thereto by diametrically opposed screws 7. The plate 6 is also provided with a centrally located rectangular orifice 8, for a purpose later on set forth, and is attached to the center-post cross-wall by diametrically opposed screws 6'.

Slidably fitting the bore 9 of the casing 1 is a tubular member or plunger 10 embodying at one end an outwardly-directed rectangular-section latch 11 having a rounded vertical edge 12 and inclined face 13, for passage through a registering rectangular hole 14 in the adjoining wall of 55 the center-post 15 and abutting coaction with

the confronting side portion 16 of the car front-door 17, as readily understandable from Fig. 3.

Conveniently, although not essentially, the plunger 10 is cylindrical, and in the bore 18 thereof a relatively reciprocative plunger 19 engages; said plunger 19 being preferably of round section and restrained against rotation, with respect to the plunger 10 by a set-screw 20 threaded into a longitudinal slot 21 in the former. The outer end of the plunger 19 is suitably rounded or shaped at 22 for operative engagement with the confronting edge wall 23 of the rear door 24, while said plunger is reciprocative through a hole 25 in the adjoining wall of the center-post 15. It is to be here noted that the plunger 19 is of a length adapted for installation of the locking device in the widest center-post of standard cars, so that its outer end may be cut-off and shaped as at 22, as required for center-posts of narrower dimensions lengthwise of the automobile or car.

If desirable a wear-plate 26 may be secured in the front-door side wall 16 as by screws 27, Fig. 3; while a well or bolt-socket 28 can be similarly attached, by screws 29, in the rear-door end wall 23, as clearly understandable from an examination of Figs. 2, 3, and 6.

A spring 30 in the bore 18 of the tubular plunger 10 serves to influence the solid plunger 19 outwards, as defined by the screw and slot connection 20, 21. Similarly a spring 31 intermediate the inner end of the plunger 10 and the confronting face of the casing end 2 operates to normally influence the latch 11 outwards, while the extent of such movement is limited by the shouldering 32 surrounding said latch.

From the foregoing it will be clearly apparent that the respective plungers 10, 19 being spring-influenced outwards in respect to the center post 15, or the door frames 42, whenever the car front-door 17 is opened the associated latch 11 and lock plunger 19 will both be released from active position in the respective engageable holes 14, 8 and 25. On the other hand, as the rear-door 24 closes, the inner edge 31 thereof on impacting the rounded end 22 of the plunger 19 forces the latter inwardly of the center post 15 in opposition to the spring 30, or telescoping said plunger 19 relative to the tubular plunger 10. Similarly, should the rear door 24 be closed, it will be equally well apparent that as the inner edge 32, of the front door 17 closes, said edge will engage the inclined face 13 of the latch 11 and thereby telescope the tubular plunger 10 relative to the plunger 19 in opposition to the spring 31 with concurrent movement of the rounded end 22 of the latter plunger into rear door locking position under action of the spring 30. Furthermore, by provision of free movement for the plunger 19 and its rounded end 22, the rear door 24 can be closed at any time regardless of the position of the front door 17; however, as the tubular plunger 10 moves inwardly of the casing 1, compression force is exerted on the spring 30 and thereby forcing the plunger 19 into active rear-door locking position until such force is released by opening the front door 17, whereupon the spring 31 reacts to restore the latch 11 to projected location relative to the center post 15. It is also noteworthy that when both doors 17, 24 are open the plunger latch 11 projects beyond the for-

ward face of the center-post 15, whereas the plunger end 22 is retracted just inside the hole 25 of said post. Again, by making the casing 1 and hollow plunger 10 of an overall longitudinal dimension for accommodation within the narrowest type of center-post 15, with a dimension when the plunger 19 is fully projected similarly appropriate for the widest type center-post 15, it will be clearly evident that only one standard make is necessary as the plunger 19 can be easily cut-down, as hereinbefore explained, to suit intermediate widths of such center-posts. Also by making the casing 1 and plunger 10 cylindrical in cross-section, with the plunger 19 of round bar stock, the material and manufacturing costs of production are reduced to a minimum, while a complementary simplification of assembly and installation over known types of analogous devices are obviously attained. In other words, by this invention no change or variation in standard center-posts 15 is required or necessary, neither is any special form of car framing component essential; whereas for purposes of installation all that is needed is to form the holes 14, 25, and fit in the pair of attaching screws 27; while it will be clearly evident that by making and assembling the few parts of the improved locking devices as shown and described herein are productive of a direct-acting freely-operative unit with the relatively movable parts all assembled in one casing.

Having thus described our invention, we claim:

1. In a locking device for opposingly swingable doors with an intervening edge engageable hollow post, the combination of a cylindrical casing having a centrally apertured wall at one end, and a surrounding flange at the other end; a closure for said flanged end with means for jointly attaching it and the tubular casing transversely within the post; a tubular plunger in the casing having a coaxial rectilinearly contoured latch projection within the circumferential confines of one end, said projection being movable through a corresponding section hole in the casing flanged end closure; a round-section solid locking member slidable in the bore of the tubular plunger for projection through the aperture in the cylindrical casing end wall; said locking member and tubular plunger latch projection having their outer extremities inclined for sliding coaction with the respectively confronting door edges; spring means in the cylindrical casing influencing the tubular plunger outwards; spring means in the tubular plunger similarly influencing the locking member outwards; and a pin engaged through the tubular plunger with projection into a longitudinal groove in the locking member to prevent relative rotary motion while permitting a definite extent of relative axial movement.

2. The combination of claim 1, further characterized in that the cylindrical casing flange is in the form of an angle-section rim, a rectangular attaching plate having a central recess affords seating reception for said casing rim, a pair of diametrically opposed screws secure the casing rim in the plate recess, and another pair of similarly related screws secure the attaching plate within the hollow post.
